UNITED STATES PATENT OFFICE.

THOMAS E. TAYLOR, OF MANSFIELD, OHIO, ASSIGNOR TO THE TAPPAN STOVE COMPANY, OF MANSFIELD, OHIO, A CORPORATION OF OHIO.

STOVE STRUCTURE.

Application filed January 15, 1925. Serial No. 2,505.

To all whom it may concern:

Be it known that I, THOMAS E. TAYLOR, a citizen of the United States, residing at Mansfield, in the county of Richland and State of Ohio, have invented certain new and useful Improvements in Stove Structures, of which the following is a specification.

My invention relates to improvements in stove structures, the present improvements being particularly designed and adapted for use in connection with gas stoves of the range type.

The primary object of the invention is the provision of an improved flue and chamber forming structure above the burner box and below the cooking top portions of the stove or range, said structure being of box-like or pan formation and divided into compartments forming heat generating chambers receiving suitable burners through suitable burner receiving openings forming the sole source of secondary air supply from the burner box, said flue and chamber forming structure being adapted to cooperate with a cooking top of the closed or solid type and being provided at its rear with suitable port openings leading to a suitable cooking top flue for the outlet of the products of combustion from said burners and through said separate heat generating chambers.

A further and important object is the provision of a flue and chamber forming structure for the cooking top portion of the stove or range which will not only improve combustion at the burners through the supply of secondary air solely through the base portions of the fuel burners but will enable the latter to be mounted a relatively fixed distance from the cooking top irrespective of whether such top is of the closed or of the open type, thereby enabling such different types of cooking tops to be used interchangeably.

A still further and important object is the provision of an improved form and arrangement of heat insulated oven, together with an improved form and arrangement of cooking top and oven flues and ports adapted to provide a maximum amount of heat with a minimum consumption of fuel.

With the above mentioned and other ends in view, the invention consists in the novel construction, arrangement and combination of parts, hereinafter described, illustrated

in some of its embodiments in the accompanying drawings, and particularly pointed out in the appended claims.

Referring to the drawings, forming a part of this specification, Figure 1 is a fragmentary perspective view of the burner box and heating chamber portions of a gas range of the side oven type, constructed in accordance with this invention, the cooking top section being removed for the purpose of clearer illustration of the parts.

Fig. 2, a perspective view of a cooking top section of the closed or solid type, removed.

Fig. 3, a similar view of a cooking top of the open or sectional grate type, removed.

Fig. 4, a fragmentary front elevation, partly in transverse vertical section, of the heat insulated oven portion of the improved range.

Fig. 5, a fragmentary horizontal sectional view of the same, taken on line 5-5 of Fig. 4.

Fig. 6, a similar view, taken on line 6-6 of Fig. 4 and illustrating in particular the relative arrangement of the cooking top and oven flue.

Fig. 7, a vertical sectional view, taken on line 7-7 of Fig. 4.

Fig. 8, a vertical fragmentary sectional view, taken on line 8-8 of Fig. 4, illustrating in particular the transverse cooking top flue and port arrangement.

Fig. 9, a fragmentary front elevation, partly in transverse vertical section, of the heat insulated oven portion of the range, showing a modified arrangement of the oven flues and ports.

Similar numerals of reference designate like parts throughout all the figures of the drawings.

While in the present instance I have shown my improvements applied to or incorporated in a gas range of the insulated side oven type, it will be apparent and should be understood that the improvements may be applied to stoves or ranges of widely varying forms or types.

The stove or range body may be formed in any suitable and convenient manner, and in the present instance, the burner box 1, is surrounded by a cooking top frame 1^a, the manifold pipe 2, being connected to the fuel burners 3, through the neck portions 3^a, in the usual or conventional manner. The burn-

ers 3 may be of any suitable and convenient form being, in the present instance, of the ring type with a large central opening 3^b, for the passage of secondary air upwardly 5 from the burner box 1.

As a means of forming suitable flues and heat generating chambers and providing for the proper location and combustion with respect to secondary air, a suitable flue and 10 chamber forming structure is interposed between the burner box 1 and the cooking top, said structure, in the present instance, being in the specific form of a pan or box-like structure consisting of a bottom section 4, and sides and ends 4^a and 4^b arranged, in the 15 present instance, within the top frame 1^a and divided into separate compartments by means of a partition 4^c. The compartments form separate heat generating chambers beneath 20 the cooking top section and as a means of supplying secondary air solely to and through the base portions of the burners 3, the bottom portions of the flue and chamber forming structure are provided with burner 25 receiving openings 4^d, preferably mounted near the front portions of the compartments or heating generating chambers and said structure or pan terminating at its rear in 30 ports 4^e, communicating with a transversely extending or horizontal cooking top flue 4^f. It will be seen that the heat and other products of combustion passes unobstructedly 35 from the fuel burners through the heat generating chambers to the ports 4^e and into the cooking top flue 4^f at the rear, the flue 4^f passing, in the present instance, over to the rear wall of the insulated oven to cooperate with the flues and ports of such structure, 40 as hereinafter referred to.

When a cooking top of the closed or solid type, such as the solid top type 5, is used and as shown in Fig. 2 of the drawings, it will be apparent that relatively large unobstructed 45 areas are provided beneath the cooking top and which are adapted to be heated by the products of combustion passing back through the heat generating chambers and beneath the cooking top section, the burners being mounted at the front and remote from the 50 outlet ports 4^e for the products of combustion. If desired, however, a simmer burner 3^e, may be provided at one side and extending through a burner receiving opening 3^b for the passage of secondary air, but in such 55 instance, it will be observed, that the top of the burner 3^e extends flush with the bottom portion of the flue or chamber forming structure like the main fuel burners 3, thereby not obstructing the passage of the products of 60 combustion through the chambers and beneath the relatively large area of the closed cooking top section above referred to.

The arrangement of the chamber forming 65 structure with respect to the relative disposition of the burners and the secondary air

inlet openings thereto is such that the fuel burners may be mounted at a relatively fixed distance from the cooking top so that removable cooking top sections of either the closed or open type may be used interchangeably 70 without raising or lowering the burners, as is now common practice with the ordinary forms of burner box and burner construction.

In Fig. 3 of the drawings a cooking top of 75 the open or sectional grate type 6, is provided and, in the present instance, as a convenient means of removably mounting and supporting the pan shaped or chamber forming structure, the upper marginal edges of 80 the side and end walls 4^a and 4^b, respectively, are provided with outwardly extending flanges 4^c, adapted to rest on the inner marginal edges of the cooking top frame 1^a.

The cooking top flue 4^f extends horizontally into one side and between the inner and outer walls of the heat insulated oven 7, and 7^a, respectively, forming a common flue for receiving the products of combustion arising from the burners in the cooking top and the oven burner 8, as now described. The side or glider members 9, within the sides of the baker oven and extending upwardly from the oven bottom 10, afford side flues 9^a, within the oven and communicating between the broiler and baker ovens. The products of combustion thus pass upwardly through the flues 9^a and into the upper portion of the baker oven and are thence conducted downwardly and rearwardly to the port 11 in the rear wall and near the bottom portion of the oven, said port 11 intersecting the end of the rear oven flue, the flue port 12 being off-set to the side of the port 11 and the flue port 12 being covered by a pipe, or elbow 13, at the rear as a common discharge port for the cooking top burners and the oven burner. 100

As a means of heat insulating the walls of the baker and broiler ovens, the inner and outer walls 7 and 7^a, respectively, are provided with an interposed heat insulating filler material 7^b, of mineral wool, or the like. The spaced walls of the oven being thus insulated less heat is radiated from the walls than in the ordinary non-insulated oven and considerable economy is effected in the way of conserving and utilizing the heat units in the oven and cutting down the consumption of fuel required. 110

In Fig. 9 of the drawings I have shown another arrangement of oven flues in which the horizontally extending oven flue at the rear and the port 11, hereinbefore described, are dispensed with and replaced by a vertically extending oven flue 14, intersected near the upper and lower rear portions of the oven by means of port openings 14^a and 14^b, respectively. 115

Having thus described some of the embodiments of my invention, without having 120

attempted to set forth all the forms in which it may be made, or all the modes of its use, what I claim and desire to secure by Letters Patent is,—

5. 1. A gas range, including in combination, a burner box provided with a pair of heat generating chambers terminating at their rear in a transversely extending flue, a closed cooking top covering said chambers, burners mounted in the forward ends of said chambers, and means for supplying secondary air solely to the base portions of said burners.
10. 2. A gas range including, in combination, a plurality of heat generating chambers provided with fuel burners extending through the bottom portions thereof and having flue ports at the rear for the outlet of the products of combustion, a closed cooking top covering said chambers, and a burner box arranged to supply secondary air solely through said burners to said heat generating chambers.
15. 3. In a stove, a stove body including a burner box, a structure superposed above said burner box and divided into heat generating chambers, fuel burners extending from said burner box into said chambers and receiving secondary air through said burner box, said structure being provided with a transverse flue and port openings at the rear of said chambers, and a cooking top above said heat generating chambers.
20. 4. In a stove structure, a stove body including a burner box surmounted by a structure divided into separate heat generating chambers above said burner box, fuel burners extending through the bottom portions of said chambers and receiving secondary air solely through said openings, said structure being provided with a flue at the rear of said chambers and burner openings, and a cooking top removably mounted above said heat generating chambers of said structure.
25. 5. A gas range, comprising a burner box provided with a pan having openings therein to receive burners and provided with a partition forming separate compartments, said compartments being provided at their rear with port openings for the outlet of combustion from the burners, burners mounted in said openings, a closed cooking top covering said pan and conjointly with said compartments forming separate heat generating chambers, and means for supplying secondary air beneath said chambers and to said burners through said burner receiving openings.
30. 6. In a gas range, including a closed cooking top and a burner box for supplying secondary air, a structure interposed between said burner box and closed cooking top and provided in its front bottom portions with openings to receive burners from said burner box and provided at its rear with port openings for the outlet of the products of com-
- bustion from said burners, said structure being divided into a plurality of heat generating chambers receiving secondary air solely through said burner openings and conducting the products of combustion to said port openings.
35. 7. In a gas range, including a closed cooking top and a burner box for supplying secondary air, a box-like structure between said burner box and closed cooking top and provided in its bottom with openings to receive burners in said burner box and provided at its rear with ports for the outlet of the products of combustion from said burners, said box-like structure including a plurality of separate heat generating chambers receiving secondary air solely through said burner receiving openings and about the burners therein and conducting the products of combustion through said chambers to said ports.
40. 8. In a gas range, a range body provided at one side with a cooking top and an oven at the other, said range body being provided at its rear with a horizontally extending flue and said oven being provided at its rear with a flue communicating with said flue of said cooking top, said oven being also provided with vertically extending side flues, discharging into the upper portion of said oven and an off-set flue port portion communicating with said oven and cooking top flues.
45. 9. In a gas range, a range body provided at one side with a cooking top and an insulated oven at the other, said range body being provided at its rear with a horizontally extending flue communicating with said cooking top, and said oven being provided with an oven burner beneath its bottom and having side flues terminating in the upper portion of said oven, said oven being also provided at its rear near the bottom portion thereof with a port for carrying off the products of combustion from said oven.
50. 10. In a stove, a stove body provided at one side with a cooking top and an insulated oven at the other, said stove body and insulated oven being provided at their rear with a common horizontally extending flue and said oven being provided at its rear bottom portion with a port communicating with said common flue of said cooking top and oven, said stove body including vertically extending side flues within the sides of said oven communicating with the interior of said oven and the latter being provided near its rear bottom portion with a flue port intersecting said longitudinally extending oven and cooking top flues.
55. 11. In a gas range, including a cooking top at one side and baker and broiler ovens at the other, a cooking top flue at the rear extending horizontally within the rear walls of said ovens and provided with a discharge port intersecting the rear wall of the baker.

- oven near the bottom thereof, said baker oven being also provided at its sides with vertically extending flue forming walls affording communication between the baker 5 and broiler ovens and discharging into the upper side portions of the baker oven, said cooking top flue being provided with a common discharge flue off-set from said oven discharge port.
- 10 12. In a range, a range body including a cooking top having heat generating chambers terminating at their rear in ports, said range body being provided with an oven and a cooking top flue communicating with said 15 chambers and extending horizontally to the rear of said oven, and said oven being provided with a subjacent oven burner and side flues for conducting the products of combustion from said oven burner to the upper interior portion of said oven, said oven having 20 its rear wall provided with a port opening near the bottom portion thereof communicating with said cooking top flue, the latter being provided with a common discharge flue intermediate said ports leading from 25 said cooking top and oven.

In testimony whereof I have affixed my signature.

THOMAS E. TAYLOR.
